UNITED STATES PATENT OFFICE.

FRANK A. DUPRAT, OF AKRON, OHIO.

SHADE-BRACKET.

1,371,878.

Specification of Letters Patent. Patented Mar. 15, 1921.

Application filed November 13, 1919. Serial No. 337,749.

To all whom it may concern:

Be it known that I, FRANK A. DUPRAT, a citizen of the United States of America, residing at Akron, in the county of Summit 5 and State of Ohio, have invented new and useful Improvements in Shade-Brackets, of which the following is a specification.

The object of the invention is to provide a simple, inexpensive and efficient shade and 10 curtain supporting bracket adapted for application to a window casing without involving the mutilation or marring of the latter and yet designed to support the shade roller and such drapery as may be desired, 15 in proper position with relation to the window opening and under such conditions as to permit of the adjustment of the shade at the will of the operator.

With these objects in view the invention 20 consists in a construction and combination of parts of which a preferred embodiment is shown in the accompanying drawing, wherein:

Figure 1 is a front view of the device applied in the operative position to a window casing.

Fig. 2 is a sectional view on the plane indicated by the line 2—2 of Fig. 1.

Fig. 3 is a sectional view on the plane 30 indicated by the line 3—3 of Fig. 1.

Fig. 4 is a detail sectional view of the hanger stud by which the bracket is secured to the window casing.

Fig. 5 is a detail view in perspective of 35 one of the brackets detached.

Fig. 6 is an end view of the same.

The bracket proper as indicated at 10, is of angular form having a main plate 11 and an upper terminal ear 12 disposed in a plane 40 substantially perpendicular to that of the plate, the latter having a keyhole slot 13 for engagement with the flattened shank 14 of a screw stud 15 of which the threaded shank 16 is adapted to be engaged with 45 the side of the casing indicated at 17. In applying the bracket the enlarged portion of the keyhole slot is passed over the head 18 of the screw stud so as to permit of the engagement of the extension 19 of the key-

hole slot with the flattened shank 14 of the 50 stud to the end that the bracket is held in an upright position with relation to the window casing as indicated in Fig. 1.

The horizontal ear 12 of the bracket is provided with a seat 20 in communication 55 with a slot 21 adapted for engagement by a terminal hook 22 on a curtain rod supporting arm 23 which rests in the seat 20, the inturned extremities 24 of said arms being engaged with the extremities of a curtain pole 25 which extends transversely of the window casing in front of and in parallelism with the shade roller 26 of which the terminal trunnions are engaged respectively with bearings 27 provided in the plate 60 or body portions of the oppositely disposed brackets.

Obviously the curtain pole supporting arms 23 may be dismounted when not required and may as readily be remounted 70 when it is desired to support a curtain or other drapery in front of the shade roller, and a movement of the latter in the adjustment of the shade can be effected as in the ordinary practice without in any way 75 interfering with such drapery and without being interfered with thereby.

To dismount the bracket from the casing it is simply necessary to raise the plate sufficiently to permit of the registration of the 80 enlarged portion of the keyhole slot 13 with the head of the screw stud, the latter being relatively inconspicuous so that it may be permitted to remain in position until it is desired to replace the bracket. 85

What is claimed is:

A shade roller bracket having a plate provided with means for detachably securing the same to a window casing and having an inturned terminal ear provided with a seat 90 and a communicating slot, and a curtain pole supporting arm adapted for arrangement in said seat and provided with a terminal head for engagement with the slot, said arm having an inturned terminal for 95 engagement with a curtain pole.

In testimony whereof I affix my signature.
FRANK A. DUPRAT.
